GAME TABLE

Josiah Tazelaar, Grand Rapids, Mich.

Application December 10, 1934, Serial No. 756,713

9 Claims. (Cl. 273—42)

This invention relates generally to a game and more particularly to a game table upon which miniature ten pins may be placed and the game of ten pins played in a manner similar to that now commonly played upon full sized alleys and designated by the term "bowling".

Briefly described, my invention consists of a table which may be adjusted to two different heights and my novel basket construction, including a pivoted shield and templet, is detachably positioned at one end of the table.

Some of the many advantages of my invention are:—the gutters of the alley are very simply formed; the protruding end of the table tensions the canvas forming the basket and also this protruding end aids in spacing the side walls of the basket; the shield located over the basket also serves as a templet thus eliminating material; the basket is readily collapsible; and finally the templet is easily moved from operative to inoperative position.

Other advantages and features of my construction reside in its construction whereby it may be economically built and whereby the several functions necessary to this game may be quickly and speedily performed.

In the drawings:—

Fig. 1 is a plan of one end of the table equipped with my novel basket construction.

Fig. 2 is a cross sectional view through Fig. 1.

Fig. 3 is a view in section taken along the line 3—3 of Fig. 2.

Fig. 4 is a fragmentary sectional view taken along the line 4—4 of Fig. 2.

Fig. 5 is a sectional view through one end of my novel table.

Like numerals refer to like parts in the several views.

The table construction consists of a top member 10, this forming the alley upon which the balls are rolled, sides 11 and end cross members 12. The end cross members 12 hold the side members 11 in spaced parallelism and these side members extend upwardly above the alley member 10 as shown in Figs. 2, 3 and 5. The top or alley member 10 is of lesser width than the spacing of the side members 11 and consequently gutters 13 are formed at each side thereof. Quarter round members 14 are located adjacent the outer sides of the gutters as clearly shown in Fig. 3. The side members 11 have holes 33 extending downwardly therein for a purpose to be described later.

Referring now to Fig. 5, numeral 16 indicates a cross member which is slanted as shown and

a leg 17, pivoted at 18, is held in position against the cross member 16 by means of the turnbuckle construction 19 which is fastened at one end to a brace 20 and at its other or upper end to the end cross member 12. It is to be understood that there are four legs 17, two at each end of the table and that a brace 20 extends between each of these pairs of legs.

An auxiliary leg 21 is hinged at 22 to the leg 17 and a hook 23 maintains these legs in alined relationship. A second brace 24 extends between these auxiliary legs to strengthen the same. A lag screw 25 is provided in each of the eight legs and serves to adjust the height of the table at various points. A hook 26 is provided at the lower end of the auxiliary leg 21 and an eyelet 27 is located in the leg 17.

From the construction shown it will be seen that the auxiliary leg 21 may be turned upwardly about the hinge 22 after the hook 23 has been unfastened and the hook 26 then inserted into the eyelet 27 and thus this auxiliary leg will be held out of use and the lag screw 25, received in a recess 28 when the auxiliary leg is positioned therebelow, will carry the table and hold it in a relatively low position.

Referring now to the basket construction, numeral 30 indicates the two sides of the basket and these have offset downwardly extending portions 31 and laterally extending portions 32.

The portions 32 have dowels 15 which fit into the holes 33, previously mentioned, and brackets 34, see Figs. 1, and 2, are attached at 35 onto the top surface of the sides 11 of the table. Thus the basket sides 30 are held in parallelism. It is also to be noted that the table top 10 extends between the offset portions 31 of the basket sides and also aids in maintaining them in properly spaced relationship.

A spacer bar 36 is pivoted at 37 onto the top edge of one of the basket sides and its opposite end carries a clip 38 which straddles the other basket side when the construction is assembled.

Referring now particularly to Fig. 1, numeral 40 indicates a cross arm which connects the side arms 41 and a sheet of pressed wood 42, having openings 43 therein, is fastened to all three of these arms. The rough side of this pressed wood, indicated at 44 in Fig. 2, is positioned as shown and therefore contacts against the top surface of the alley 10 when the templet is positioned as shown in Fig. 2. Each of the side arms 41 has an upwardly extending portion which is slotted at 46 and pivotal means 47

extends through each of these slots into the respective basket side 40. The U-shaped construction may be swung upwardly to a position against the spacer bar 38. This is shown in 5 dotted lines.

A piece of canvas 50 is fastened along the vertical rear edges of the basket sides by means of cleats 51 and the tacks 52, see Fig. 3, and a reinforcing padding 53 is located thereagainst as 10 shown. The canvas is also tacked to the outer lower sides of the offset portion of side members 30 and is extended upwardly at the inner side of the offset portion as clearly shown in Fig. 2. This upward extension is indicated by 15 the reference numeral 55. The end cross member 12 of the table, see Figs. 4 and 5, protrudes beyond the ends of the sides 11 and thus the canvas extension 55 is tensioned by engagement against this offset portion as clearly shown in 20 Fig. 4. Thus a taut basket is formed for receiving the pins when they are thrown rearwardly by the contact of the ball thereagainst. The ball may be propelled by means of a cue or 25 else simply rolled.

25

The operation

The operation is easily understood. The device is assembled and fastened onto the table 30 as shown in Fig. 2 and the pins are located within the templet 42, the slots 43 serving to guide them to their exact positions. The protruding end of the alley pushes the canvas rearwardly and tautens the same as will be understood from 35 an inspection of the drawings. The templet is then raised to the dotted line position shown and in this position it serves to hold the spacer bar in place and of more importance it serves as a shield to prevent the pins from flying out 40 of the basket. The impact of the ball against the pins causes them to be thrown rearwardly and scattered and to usually strike against the padding 53 and then drop into the basket.

Next, the templet is swung downwardly as 45 shown in Figs. 1 and 2 and then the pins are manually inserted in the larger part of the several openings 43 and thence slid forwardly to their correct positions. The templet is now slid forwardly along the alley until the pivots 47 50 contact the rear of the slots 46 and then the templet may be turned upwardly to its dotted line position.

The invention is defined in the appended 55 claims and is to be considered comprehensive of all forms of structure coming within their scope.

I claim:

1. In a game table construction, the combination of, a basket having two elongated sides, brackets located at one end of each of these sides, a spacer bar pivoted to one of the basket sides at its other end, a clip fastened to the end of the spacer bar and adapted to straddle the other side of the basket and shielding means pivoted between the basket sides and adapted 60

to rest upon the said spacer bar when located in one of its positions.

2. A combination of elements as recited in claim 1, in which the pivoted shielding means is adapted to be tilted downwardly to a second 5 position, said shielding means having a plurality of openings therein and serving as a templet when in its said second position.

3. In combination, a table having vertically located sides and a top located between and 10 below the edges of the sides, said top being of lesser width than the space between the sides whereby gutters are formed between the top and each of the sides, cross members located underneath the top to hold the sides in spaced relationship, basket sides fastened along the top edges of the sides at one end thereof so as to extend in cantilever fashion therefrom, said basket sides having depending portions which extend to a plane below the top of the table, 15 a piece of canvas fastened to these depending portions and extending upwardly at the ends of the basket sides which are spaced away from the table and means for detachably connecting the basket sides at the upper edges whereby they 20 are held in spaced relationship.

4. A combination of elements as set forth in claim 3 in which the means for fastening the basket sides to the top edges of the sides of the table are made detachable. 25

5. A construction as recited in claim 3 in which shielding means is pivoted between the sides, said shielding means resting upon the detachable means.

6. A construction as recited in claim 3 in which 35 shielding means is pivoted between the sides, said shielding means being capable of being swung upwardly to serve as a shielding means or to be swung downwardly to a position adjacent the top surface of the table.

7. In combination, two basket sides having 40 respective offset portions extending downwardly adjacent one end thereof, canvas fastened to these offset portions and extending upwardly to form a basket, a U-shaped frame pivoted between the sides of the basket, a templet fastened to the U-shaped frame, one side of the templet being roughened for the purpose described.

8. In combination, a game table having an 45 offset end, a basket including a frame with flexible unsupported material across one side thereof, and means for maintaining the said one side of the basket against the offset table end whereby the flexible material must follow 50 the outline of the offset and consequently be tautened.

9. In combination, two spaced members held 55 in parallel relationship, a templet pivoted therebetween, said templet having a flat member with a series of elongated openings therein for the 60 purpose described, said pivot of the templet including a slot whereby the templet may be slid longitudinally.

JOSIAH TAZELAAR. 65
